UNITED STATES PATENT OFFICE

150,536

DESIGN FOR A HAND TANK TRUCK

Rufus H. Barrett, San Francisco, Calif., assignor to California Research Corporation, San Francisco, Calif., a corporation of Delaware

Application July 22, 1946, Serial No. 131,787

Term of patent 3½ years

(Cl. D14—3)

To all whom it may concern:

Be it known that I, Rufus H. Barrett, a citizen of the United States of America, residing at 1910 21st Avenue in the city and county of San Francisco and State of California, have invented a new, original, and ornamental Design for a Hand Tank Truck, of which the following is a specification, reference being had to the accompanying drawing, forming part thereof.

This is a continuation-in-part of my copending application Serial No. D. 119,540, filed May 14, 1945, now abandoned.

The characteristic features of my design reside in the portions shown by means of full lines in the drawing.

I claim:

The ornamental design for a hand tank truck, as shown and described.

RUFUS H. BARRETT.
